UNITED STATES PATENT OFFICE

2,525,962

ARTIFICIAL TOOTH

Sidney I. Silverman, Brooklyn, N. Y.

Application December 13, 1946, Serial No. 715,977

1 Claim. (Cl. 32—8)

1

This invention relates generally to the construction of artificial teeth, but more particularly to a means and method used in the construction of both dentures and teeth and the articulation of the latter.

One object of the invention is to increase efficiency and skill in denture service, particularly for the war casualty.

Another object of the invention effects a reduction in adjustment time for each denture patient, reducing the use of dentist's time, equipment and space.

A further object of the invention is that it effects a reduction in expenditure of man hours of dental technicians.

Another object of the invention is that it reduces the cost of the artificial teeth and also reduces stock inventories of artificial teeth.

Still another object of the invention is to obtain a more perfect articulation between upper and lower dentures.

Referring to the figures in which like parts are represented by similar reference characters:

Figure 1 is a side elevation of an articulator showing the teeth and rings set up in wax;

Figure 2 is a sectionized elevation showing the wax denture inclosed within the investment flask, the section being taken through rings on upper right and left molars;

Figure 3 is a sectional view of the investment flask opened after having eliminated the wax, and showing the rings retained within the plaster;

Figure 4 is a perspective illustrating the ring construction;

Figure 5 is a sectionized view of a molar showing the improved cusp formation, the section being taken on a buccal-lingual plane;

Figure 6 is a top plan view of the tooth showing the occlusal surface of the tooth illustrated in Figure 4;

Figure 7 is an elevation of the tooth illustrated in Figure 4 showing a buccal-lingual view;

Figure 8 is an elevation of the tooth illustrated in Figure 4 showing a mesial-distal view; and

Figure 9 is a sectionized view of the ring tooth, the section being taken at the ridge lap.

Briefly stated, the invention relates to a method and means for forming artificial teeth in which the side walls of a tooth are formed by a prefabricated ring which surrounds a core, the core being formed integral with the denture and extending beyond the ring to include the occlusal surface. The ring and the core are formed of the same material and the portion of the core which

2

extends beyond the ring and on which are formed the cusps is of plastic which matches the rest of the tooth in color and shade. The cusps of the teeth are formed on the wax model, before investing, by occlusion with teeth of the opposite jaw.

The new teeth 10 have the dimensions and shades equivalent to those generally used in the practice of dentistry. They differ, however, in that the cusps 11, instead of being fabricated in a plastic resin or porcelain material, are fabricated with a malleable wax or similar tractable material. In the formation the wax cusps 11 are placed on a prefabricated plastic ring 12 which has the contours of the buccal, lingual and proximal surfaces of various molds and shades of artificial teeth. The plastic ring 12 is provided with a central channel 13 which is beveled at one end as indicated by the numeral 14. The wax cusps 11 are contiguous with the wax which fills the hollow plastic ring 12. The wax within the plastic ring completes the ridge lap surface of the tooth.

The following procedure is recommended for the establishment of the cusp inclinations for each occlusal relationship. An upper set of teeth with preformed cusps with 10, 20, 30 or 40 degree cusp inclinations is matched by the lower wax cusped teeth with corresponding cusp inclinations. The teeth are set up on the articulator 15 with the vertical dimension opened $\frac{1}{2}$ to 1 millimeter, which is accomplished by setting the adjustable stop member 16 to provide this clearance. The teeth may then be recontoured in the mouth or on the articulator by directing either the jaw or the articulator through all the occlusal excursions until the vertical dimension has closed down the height it was originally opened. Satisfactory guides are available to control the degree of closure of the vertical dimension.

The teeth may be set up and contoured on base plate wax and the denture base and cusps be processed in one investment. When the denture case is invested and the wax is boiled out the occlusal surface may be packed with acrylic resin or any other plastic through the hollow center or channel 13 of the tooth. The cusps may be packed from either the occlusal or ridge lap side of the tooth.

The tooth can be made in all molds and shades which the dental profession uses. The design of the tooth is adapted to the mold of each of the 28 natural teeth which the dental profession replaces. The teeth can be used for replacing eden-

tulous mandibular and maxillary restorations, partial dentures and fixed bridge restorations. The plastic rings 12 with wax cusps are easily and quickly produced and standardization of a mean cusp reduces the supply problem considerably. The manufacturing cost of the rings is low and the procedure followed for the formation of the dentures is simple, and includes the following operations in the order specified below:

1. Impressions of the mouth of the patient are made in the usual manner;

2. From the impressions the customary plaster models are made, on which are formed wax dentures provided with built-up wax rims (not shown). These dentures are tried in the patient's mouth to obtain a bite record as in the ordinary procedure;

3. After fitting these wax dentures in the patient's mouth and adjusting them to the proper bite, they are mounted on the articulator 15, and the stop member 16 of the articulator set so that there will be a clearance between the rims of $\frac{1}{2}$ to 1 millimeter;

4. On the articulator the wax cuspid teeth rings are set up in position and opposite fully fabricated plastic teeth, with any degree of cusp heights suitable to requirements of the patient, are set to articulate with the wax teeth;

5. Wax cusps are molded into proper shape by excursions of the natural jaw or by movement of the articulator arms until the bite is closed to the $\frac{1}{2}$ to 1 millimeter it was opened on the articulator;

6. Molding in the mouth with the use of a central bearing point device automatically corrects the centric record;

7. The opposite or fully fabricated denture is processed in the regular manner. The base with the wax cuspid teeth (ring teeth) is similarly invested in a flask 17 (Figs. 2 and 3) as for a routine denture;

8. When the wax is boiled out the rings are retained in the investment plaster, as shown in Figure 3; and

9. The cuspid area which was in wax before the wax was eliminated from the flask is packed with appropriate color plastic, and the denture base area is packed with appropriate base material.

5 The tooth plastic and the base plastic are packed and processed in one investment.

A separator is used in packing. Tin foil may be used over the cusps or any commercial plastic separating medium may be placed within the channel after elimination of the wax.

10 The ring teeth may be made from any of the plastic materials which the dental profession uses for the manufacture of artificial teeth and the ring may be arranged in either the upper or lower denture or in both so long as the tooth opposite the ring tooth is either a complete artificial tooth or a natural tooth from which the cusps of the ring tooth may be formed as described above.

15 Having thus described my invention, what I claim as new and wish to secure by Letters Patent is:

20 As an article of manufacture, an artificial tooth comprising an anatomically-configured body including a plastic prefabricated ring section having buccal, lingual, proximal and gingival surfaces and a central through opening beveled at one end toward the occlusal surface; and a temporary removable core of malleable wax in said opening, said core extending beyond the ring at one end to facilitate the formation of the correct cusped occlusal surface.
